UNITED STATES PATENT OFFICE.

HENRY SIEPMANN, OF SEATTLE, WASHINGTON, ASSIGNOR OF ONE-FOURTH TO A. O. STUBB, OF SEATTLE, WASHINGTON.

SUBMARINE DREDGE.

1,179,669.

Specification of Letters Patent. Patented Apr. 18, 1916.

Application filed June 30, 1914. Serial No. 848,320.

To all whom it may concern:

Be it known that I, HENRY SIEPMANN, a citizen of the United States of America, and a resident of the city of Seattle, in the county of King and State of Washington, have invented certain new and useful Improvements in Submarine Dredges, of which the following is a specification.

My invention has for its primary object 10 to provide novel apparatus of the above type which will facilitate the extraction of gold and other precious metals from the sand of ocean or other water beds.

Other objects will be set forth as my description progresses and those features of construction, arrangements and combinations of parts in which my invention resides, will be succinctly defined in my annexed claims.

Referring to the accompanying drawings illustrating a preferred embodiment of the invention and wherein like characters of reference indicate like parts throughout: Figure 1 is a longitudinal section of the invention. Fig. 2 is a transverse section on line 2—2 of Fig. 1. Fig. 3 is a similar section on line 3—3 of Fig. 1. Fig. 4 is a rear end elevation. Fig. 5 is a perspective of the invention as in use, and Figs. 6, 7 and 8 are fragmentary details.

Reference numeral 1 indicates the body of my dredge, the same comprising a hollow forwardly tapering shell having a rear wall 2, provided with a delivery opening 3 enclosed by an inturned flange 6 to which a cylindrical perforated shell 5 is secured as shown, or in any other suitable manner. Wall 5 forms a centrally placed partition for body 1, dividing the same into a through passage or sluice way 4 and an annular collecting chamber 4'. The forward edge portion of cylindrical wall 5 is riveted to body 1.

Reference numeral 8 indicates a rotatable 45 double spiral blade for forwarding material through passage 4, this being provided on its rear end portion with a gear 9 which meshes with a pinion 10 fixed to the shafts of a fluid motor, as 11, conveniently connected, by a flexible supply pipe 12 with a suitable pump 13 for supplying air or water thereto under pressure.

Body 1 is provided along its forward edge with teeth 14 which act to loosen and direct

the sand or other material of the water's bed 55 into the through passage 4.

Reference numeral 15 indicates a nose or plow of open formation projecting forwardly of body 1 and extending across the adjacent end of through passage 4 so as to, 60 in addition to loosening the material and acting as a fender, prevent the entrance of stones or other objects of undue size into the passage. Nose or plow 15 comprises a rigidly united series of arms radiating and 65 curving rearwardly where they are fixedly joined to blade 8 so as to rotate therewith.

A convenient method of operating my device consists in providing a cable 17 which is passed over a sheave 20 suitably anchored in the water and its other end being wound on drum 18 of a suitable engine 21 located on the shore. A second cable 17' is connected by chains 19 to the opposite end portions of body 1 and wound on drum 18' so that upon 75 proper rotation of drums 18 and 18' body 1 can be alternately run toward and from the beach.

Assuming that the device has been hauled out into the water, drum 18 is allowed to 80 run idle and drum 18' and pumps 15 are operated, thereby advancing the device toward the beach and simultaneously operating motor 11, fluid from which latter exhausts into the water through a pipe 24 having a suitable back check valve, as 25. During the advanced movement of the device, flexible fluid supply pipe 12 is continuously drawn in by hand. Material entering the forward end portion of through passage 4 is 85 caught by blade 8 and forwarded over the perforated shell 5 which latter is preferably provided with annular ribs 21, adapted to check the material for a more thorough separation thereof, as will be apparent. Such 90 of the material as fails to enter into collecting chamber 4', is delivered through opening 3 of wall 2, as will be readily understood.

In this connection it will be observed that wall 2 is provided with openings, normally closed by suitable closures, as 22, through which the contents of chamber 4' can be removed. Wall 2 is also provided with a series of small openings or holes 26, extending about and close to the opening 3, 105 through which water can pass out of chamber 4'. Flange 6 is suitably grooved for reception of the edge portion of gear 9 and the

lower portion thereof enlarged, to provide a chamber 6' in which motor 11 is arranged.

Reference numeral 23 indicates packing rings suitably fitted in flange 6 and bearing 5 against the side faces of gear 9 to prevent the passage of water or foreign substances into chamber 6', for obvious reasons.

The foregoing detailed description has been given for clearness of understanding 10 only, and no undue limitation is to be understood therefrom, but the appended claims are to be construed as broadly as is permissible in view of the prior art.

Having thus described my invention, what 15 I claim as new, and desire to secure by Letters Patent of the United States of America, is:—

1. An apparatus of the character described comprising a hollow tapered body 20 having one end wall provided with an internal flange, a cylindrical perforated shell secured to the flange of the body, said body being provided with a collecting chamber extending around said shell, a helical forwarding blade for advancing material over the foraminous wall, and means for rotating said blade.

2. An apparatus of the character described comprising a hollow body, a cylindrical perforated shell in said body forming 30 a passage, said body having a collecting chamber extending around said shell, a rotatable helical blade in said shell, and means on said body for rotating said blade.

3. An apparatus of the character described, comprising a cylindrical perforated shell, an outer shell secured to the perforated shell to inclose an annular chamber between them, a helical conveyer within the inner 40 perforated shell, a gear secured to said conveyer, a motor in the annular chamber and rotative connection between the motor and said gear.

4. An apparatus of the character described, comprising a cylindrical perforated shell, an outer shell secured to the perforated shell to inclose an annular chamber between them, a helical conveyer within the inner 45 perforated shell, the end of said conveyer 50 at the inlet end having conically placed screening members, a gear secured to said conveyer, a motor in the annular chamber and rotative connection between the motor and said gear.

5. An apparatus of the character described comprising a cylindrical perforated shell, an outer shell secured to the perforated shell to inclose an annular chamber between them, the rear end of the outer shell being pro-

vided with discharge openings closely surrounding the rear opening of the center cylinder, a helical conveyer within the inner perforated shell, a gear secured to said conveyer, a motor in the annular chamber and rotative connection between the motor 65 and said gear.

6. An apparatus of the character described comprising a hollow body, a cylindrical perforated shell in said body forming a passage, said body having a collecting 70 chamber extending around said shell, a rotatable helical blade in said shell, a fluid motor on said body having driving connection with said blade, and fluid supply and delivery pipes connected with said motor, 75 said delivery pipe being provided with a back check valve, for the purpose specified.

7. An apparatus of the character described comprising a body having a through passage provided with a foraminous wall, 80 a rotary blade for forwarding material through the passage of said body, and rotatable relative thereto, and a plow fixed to rotate with said blade.

8. An apparatus of the character described comprising a body having a through passage provided with a foraminous wall, 85 a rotary blade for forwarding material through the passage of said body and rotatable relative thereto, and a plow of open 90 formation fixed to and rotatable with said blade, said plow extending across the forward end of the passage of said body.

9. In an apparatus of the character described, in combination, a conically tapering 95 body having dredging jaws at its smaller end, a perforated shell within said body, a helical conveyer within said shell, cables secured at each end of said body, and means for operating said cables to draw said device back and forth along the bottom of a 100 waterway.

10. In an apparatus of the character described, in combination, a conically tapering body having dredging jaws at its smaller 105 end, a perforated shell within said body, a helical conveyer within said shell, a plow on the forward end of said conveyer, means for rotating said conveyer, cables secured to each end of said body, and a power connection for drawing said device back and forth along the bottom of a waterway. 110

Signed at Seattle, Washington, this 22nd day of June, 1914.

HENRY SIEPMANN.
